H. D. WALKER.
BEDRAIL CONNECTION.
FILED JULY 14, 1922.

INVENTOR

HUGH D. WALKER
BY *Hugh D. Walker*
ATTY

UNITED STATES PATENT OFFICE.

HUGH D. WALKER, OF GRIMSBY, CANADA, ASSIGNOR TO METAL CRAFT COMPANY,
LIMITED, OF GRIMSBY, CANADA.

BEDRAIL CONNECTION.

Application filed July 14, 1922. Serial No. 575,015.

To all whom it may concern:

Be it known that HUGH D. WALKER, a subject of the King of Great Britain, residing at Grimsby, in the county of Lincoln 5 and Province of Ontario, Canada, has invented certain new and useful Improvements in Bedrail Connections, of which the following is a specification.

My invention relates to improvements in 10 bed rail connections and more particularly to such connections for use on beds embodying the well known round or rectangular tubular posts, and consists essentially of a diagonally split reinforcement tube confined in a wedged manner within the tubular 15 posts at the point of rail connection and provided with a lateral boss projecting through a corresponding slot in the bed post, and itself provided with one or more slots to receive rail hooks.

The most vital and usually the weakest part of the modern tubular post is in the rail connections. These connections, owing 25 to the constant vibration and flexing of the bed while occupied, sooner or later tend to become loose with a result of the bed losing its original rigidity.

The object of this invention, then, is first, to provide novel reinforcement of the bed 30 rail connections, and second, to provide a connection which may be easily and readily taken apart and set up with the minimum of effort, for moving, changing the bed from one room to another, and the like.

A further object is to provide a bed rail connection of the class specified which will be simple, practical and inexpensive to manufacture.

These, together with other objects, may be 40 attained by the construction, combination and arrangement of the parts, as will be hereinafter more fully described, illustrated in the accompanying drawing, and pointed out in the claims hereunto appended.

Referring to the drawing:

Figure 1 is a cross sectional side elevation of the bed rail connection showing the bed post broken away above and below the connection and the rail broken away close 50 to the connection:

Figure 2 is a detailed side elevation of the reinforcement tube;

Figure 3 is a top sectional view taken on the line 3-3 in Figure 3;

55 Figure 4 is a top view of Figure 2;

Figure 5 is a detailed face elevation of the reinforcement tube (this would be the front elevation if it belonged to the head posts, and the rear elevation if belonging to the foot posts); and,

Figure 6 is a detailed side elevation of the rail hooks; and,

Figure 7 is a view similar to Figure 3 showing a modified form of the invention as may be applied to bed posts rectangular 65 in cross-section.

Similar reference characters refer to similar parts throughout the several views.

In the drawing a section of ordinary 70 tubular bed post is indicated by A, and a bed rail by B. Confined within the tubular post A is a heavy preferably cast iron reinforcement tube diagonally split longitudinally of its length, as shown more clearly in Figure 2. The two separate portions of 75 this split tube are indicated by C, D, the section C being plain, and the section D having formed thereon in opposed position to the section C an external boss E preferably of rectangular formation both in elevation and cross-section.

When the said reinforcement tube is placed in proper relative position in the post A, the boss E extends through a corresponding slot 2 in said post and protrudes 85 beyond the periphery of the post just a perceptible distance. The boss E is provided with one or more slots or eyes 3 for the reception of the bed rail hooks F, which will hereafter be fully described.

In assembling the device the section D of the reinforcement tube is first inserted wide end first into the post A from the bottom, the boss E readily falling into the slot 2, and thereby properly positioning this section. 95 When this first step is executed, the section C of the reinforcement tube is inserted also from the bottom, narrow end first, to a position where the contacting edges of the two sections cause an expansion against the sides 100 of the post A resulting in rigidity throughout. The section C is then retained in such position by a set screw 4, for example.

The reinforcement tube is now in position to receive the hooks F on the rail B. These 105 hooks are preferably formed integral with the rail B, and the breadth of the hooks proper at their hilts is equal to the interior diameter of the reinforcement tube when at its maximum expansion, so that the ends of the 110

hooks will engage the side of the reinforcement tube opposite to that through which said hooks effect their entrance. The hooks are preferably tapered downwardly on their innermost edges for the purpose of affording easy access to the reinforcement tube, and the rail B is provided with perpendicularly disposed lateral flanges 5 which engage the outer edge of the boss E, on the section 10 D of the reinforcement tube.

There has thus been provided a simple and efficient device of the character described and for the purpose specified.

Having now fully described my invention, 15 what I claim and desire to secure by Letters Patent, is:—

1. In a bed rail connection, the combination with a tubular bed post and a rail provided with hooks, of a reinforcement tube 20 inserted within said post, a boss formed on said reinforcement tube and protruding through a corresponding slot in said post, said boss having slots for the reception of said hooks.
2. In a bed rail connection, the combination with a tubular bed post and a rail, of a reinforcement tube inserted within said post, a boss formed on said reinforcement tube and protruding through a correspond-

ing slot in said post, and means for connecting said rail to said boss. 30

3. In a bed rail connection, the combination with a tubular bed post, and a rail, of a reinforcement tube diagonally split longitudinally of its length and capable of lateral expansion against the interior walls of said post by driving one section of the tube narrow end first alongside the other section, and means for connecting said rail to said reinforcement tube. 35

4. In a bed rail connection, the combination with a tubular bed post and a rail, of a reinforcement tube diagonally split longitudinally of its length and capable of lateral expansion against the interior walls of said post by driving one section of the tube narrow end first alongside the other section, a boss formed on one section of said reinforcement tube and protruding through a corresponding slot in said post, and means for connecting said rail to said boss. 45

In testimony whereof I have affixed my signature.

HUGH D. WALKER.
